UNITED STATES PATENT OFFICE.

BENJAMIN ADRIANCE AND AMOS CALLESON, OF BROOKLYN, NEW YORK,
ASSIGNORS, BY DIRECT AND MESNE ASSIGNMENTS, TO THE PHOENIX
CORK COMPANY, OF NEW YORK, N. Y., A CORPORATION OF NEW YORK.

BOTTLE-CAP-MAKING MACHINE.

SPECIFICATION forming part of Letters Patent No. 716,611, dated December 28, 1902.

Application filed May 20, 1902. Serial No. 108,175. (No model.)

To all whom it may concern:

Be it known that we, BENJAMIN ADRIANCE and AMOS CALLESON, citizens of the United States of America, and residents of the ⁵ borough of Brooklyn, in the city of New York, county of Kings, and State of New York, have invented certain new and useful Improvements in Bottle-Cap-Making Machines, of which the following is a specification.

The machine herein illustrated has been ¹⁰ designed for the special purpose of manufacturing the bottle-cap illustrated in United State Letters Patent No. 509,834, granted November 28, 1893, to Alfred L. Weissenthaler. This cap consists of a top plate of sheet metal and a holding-band, also of sheet metal, the ends of which are hooked together in such a manner that they can be readily detached by the fingers. One edge of the band is ¹⁵ turned inwardly to engage the top plate. Within the cap and adjoining the top plate is a compressible washer. This is preferably a cork disk.

The machine is fed by an attendant at three ²⁰ points, at the first point with strips of sheet metal of a width equal to the length of the holding-band of the cap which the machine is designed to manufacture, at the second point with other strips of sheet metal which ²⁵ are of a width suitable for cutting out the top plates of the cap, and at the third point with cork disks or washers.

The invention resides in the combinations ³⁰ of mechanical parts for automatically producing the above-described caps or portions thereof, as hereinafter specifically pointed out in the claims.

In the accompanying sixteen sheets of drawings, which form a part of this specification, ⁴⁰ Figure 1 is a front view of the machine, showing the spindle of the coiling mechanism, the dial-feed mechanism, the top plate cutting and drawing mechanisms, the edge-turning mechanism, and the cork-feed mechanism, but omitting the strip-feed mechanism for the bands, the band-cutting mechanism, and the strip-feed mechanism for the top plates. Fig. 2 is a back view of the machine, showing substantially the same parts. Fig. 3 is a ⁴⁵ view from the left-hand side of the machine. Fig. 4 is a view from the right-hand side of the machine, omitting the fly-wheel. Fig. 5 is a plan view in which the parts above the table are omitted. Fig. 6 is a plan view, drawn to a larger scale, showing a portion of ⁵⁵ the carrier-ring and the spacing-pawl of the dial-feed, the edge-turning die, detector-pin for throwing the cork-inserting mechanism into operation, and the ejector for the finished caps. Fig. 7 is a vertical longitudinal ⁶⁰ section through the strip-feed mechanism for the bands on the line $x^8 x^8$ of Fig. 9, showing the feeding-bars and the longitudinally-movable slide by which the bars are actuated at the forward point of its stroke. Fig. 8 is a ⁶⁵ similar section showing the slide at the rearward point of its stroke. Fig. 9 is a horizontal section on the line $x^9 x^9$ of Fig. 7, showing the strip-feed mechanism from underneath. Fig. 10 is a vertical longitudinal section on the line $x^{10} x^{10}$ of Fig. 11, showing the feeding-pawls shifted transversely as compared with Fig. 7 to effect the exchange ⁷⁰ of the engagement of the pawls and feeding-bars. Fig. 11 is a horizontal section on the line $x^{11} x^{11}$ of Fig. 10, showing the parts from underneath. Fig. 12 is a view of the strip-feed mechanism from the right side. Fig. 13 is a view of the strip-feed mechanism from the end. Fig. 14 is a vertical longitudinal section through one of the partition-pieces which separates the feeding-bars. Fig. ⁷⁵ 15 is a view of the strip-feed mechanism from the left side. Fig. 16 is a plan view of the strip-feed mechanism. Fig. 17 is a vertical longitudinal section at the forward end of one of the feeding-bars. Fig. 18 is a plan view of the transversely and longitudinally movable slides which carry the feeding-pawls. Fig. 19 is an elevation showing the punches and ⁸⁰ die-block for cutting the bands and the band-coiling mechanism, but omitting the strip-feed mechanism. Fig. 20 is a perspective view of the coiling-head. Fig. 21 is an elevation showing from the rear the punches and die-block for cutting the bands, the guides for turning the bands edgewise, the band-pusher, and the coiling-spindle. Fig. 22 is a vertical section on the line $x^{22} x^{22}$ of Fig. 21. Fig. 23 is a plan view showing the forward ⁸⁵ ⁹⁰ ⁹⁵ ¹⁰⁰

end of the strip-feed mechanism, the dies for cutting the band, the band-pusher, and the coiling mechanism. Fig. 24 is a side view of the mechanism for operating the coiling-spindle. Fig. 25 is a front view of this mechanism. Fig. 26 is a plan view of this mechanism. Fig. 27 is a view from the right-hand side showing the strip-feed mechanism for the top plate. Fig. 28 is a view of this mechanism from the front. Fig. 29 is a vertical section through the framework of the mechanism on the line $x^{29} x^{29}$ of Fig. 27. Fig. 30 is a vertical section through the cork-inserting and cap-ejecting mechanism on the line $x^{30} x^{30}$ of Fig. 6. Fig. 31 is the same section showing the cork inserted and the cap ejected. Fig. 32 is a section through the top plate punching and drawing mechanism on the line $x^{32} x^{32}$ of Fig. 5. Fig. 33 is the same section $x^{33} x^{33}$ of Figs. 5 and 23, showing the punch for cutting the hook and the cork-transferring mechanism. Fig. 36 is a vertical section on the line $x^{36} x^{36}$ of Fig. 6, showing the edge-turning mechanism and the detector-pin. Fig. 37 is a vertical section on the line $x^{37} x^{37}$ of Fig. 5, showing the top-plate-punching mechanism and the cork-feeding mechanism. Fig. 38 is a front view showing the adjustable connections between the yokes and the punch-head of the top plate punching and drawing mechanism, the parts at the left hand being in section. Fig. 39 is a vertical section on the line $x^{39} x^{39}$ of Fig. 5, showing the guard-rail under the carrier-ring. Fig. 40 is a perspective view showing the cork-feeding mechanism. Fig. 41 is a perspective view of a band for the cap as it is formed by the band-cutting mechanism. Fig. 42 is a perspective view of a band showing how one end is bent and its tongue thrown out for engagement with the blade of the coiling-spindle when inserted in the coiling-head. Fig. 43 is a perspective view of a top plate. Fig. 44 is a perspective view of a cork disk. Fig. 45 is a perspective view of the assembled cap produced by the machine.

50 Strip-feed for bands.—The strips of sheet metal from which the bands for the caps are cut by the machine have a width equal to the length of the band, which in the machine as illustrated is four inches. A convenient length for them is about twenty inches, and each strip cuts into thirty-six bands. These strips are laid by the attendant, one at a time, on the table 1, which is diagonally placed with respect to the general framing of the machine. There are four parallel grooves running lengthwise in the top of the table. These grooves carry two pairs of feeding-bars 2 2 and 3 3. The pairs alternate in feeding forward. At the forward end of each bar is a feeding-dog 4, which engages with the strip when it is feeding. Partition-pieces 5 separate the two feeding-bars on each side. These

are pinned fast to the table and are provided with tongues which engage grooves in the sides of the feeding-bars and guide the feeding-bars. The feeding-bars are notched along their lower edges at intervals equal to the width required for the holding-bands for engagement by the forward-feeding pawls 6 6 and the rearward-feeding pawls 7 7 7. The pawls are pivoted directly to a transversely-movable slide 8, by which they can be brought into engagement with either pair of feeding-bars as required. In Fig. 9 the two forward-feeding pawls are shown in engagement with the pair of feeding-bars 3 3 and two of the four rearward-feeding pawls are shown in engagement with the pair of feeding-bars 2 2. In Fig. 11 the engagement of the pawls and feeding-bars is exchanged, the forward-feeding pawls are shown in engagement with the other pair of feeding-bars 2 2, and the other two of the four rearward-feeding pawls are shown in engagement with the pair of feeding-bars 3 3. The engagement of the feeding-pawls with the feeding-bars is exchanged by the movement of the transversely-movable slide. This slide is carried by a longitudinally-movable slide 9, by the reciprocation of which the feeding is effected. The slide has a movement sufficient to feed the bars the space of two notches at each reciprocation; but the forward-feeding pawls are wider than the amount of transverse movement of the transversely-movable slide and also wider than the bars with which they engage, so that they will at all times be under the partition-pieces. These partition-pieces are notched at 5° to allow the pawls to rise into engagement with the feeding-bars during a portion only of the reciprocation of the slide, thereby reducing the effective stroke, so that they will only feed the bars forward one notch at each reciprocation, while the other rearward-feeding pawls, which engage with the bars throughout substantially their entire stroke, will feed the bars rearwardly two notches at each reciprocation and will have fed one pair of bars rearwardly to their extreme rear position when the other pair of bars has been fed forward half the distance. In consequence one pair of feeding-bars will be at its rearward position and resting during the last half of the time occupied in the feeding of each strip. During any portion of this time a new strip can be set in place by the attendant without stopping the machine, so that it will be fed automatically by the machine as soon as the preceding strip has been fed beyond the end of the strip which is to follow. Each new strip as it is put in place rests at the forward end on the preceding strip which is feeding, and a friction-clamp 10 is provided to prevent the new strip from being carried along by the old strip. The strips feed under a bar 11, which keeps them from buckling. The feeding-dogs on the ends of the feeding-bars feed forward only as far as the edge of the die-block, leaving the end of the strip with stock for five

bands. The forward end of the strip which is to follow butts against this and completes the feeding. The reciprocation of the longitudinally-movable slide and the feeding of the strip take place at each revolution of the main shaft 12 of the machine and are effected by power transmitted from the shaft through the crank-disk 13, pitman 14, arm 15, rock-shaft 16, arm 17, connecting-link 18, reciprocating element 19, with a rack at one end, and oscillating gear 20, with crank-pin 21 and connecting-rod 22 between the crank-pin and the longitudinally-reciprocating slide. The feeding of the strip takes place at the final movement of the reciprocating element toward the front. The transversely-movable slide for exchanging the engagement of the pawls and feeding-bars is reciprocated alternately to one side and to the other at every thirty-sixth stroke of the feeding mechanism, this being the number of strokes requisite for the feeding of a strip. A pawl 23, attached to the longitudinally-movable slide, engages a ratchet-wheel 24 with seventy-two teeth, which is rotated one tooth at each operation of the feeding mechanism. This ratchet-wheel is connected by a shaft 25 with a cam-wheel 26. There are two diametrically opposite camming-points on this wheel, by which a pin 27, carried by an arm 28, is moved transversely every thirty-sixth tooth of the ratchet movement first to one side and then to the other. This pin projects through the arm, and its upper end engages and operates the transversely-movable slide.

Band cutting and coiling mechanism.—The band *b* for the cap is formed from a straight strip of sheet metal about nine-sixteenths of an inch in width and four inches in length. Near one end an eye *e* is punched and near the other end a U-shaped slit is cut, thereby forming a tongue *t*, which is bent out from the surface of the band and engages the eye at the other end when the band is coiled, and thereby locks the two ends together. The end with the eye is rounded and is somewhat narrower than the body of the band and projects beyond the eye about seven-sixteenths of an inch. This end is lapped outside when the band is coiled and is thus formed so that it can be conveniently taken hold of by the fingers when it is on a bottle and unhooked and removed in opening the bottle. As the strip from which the bands are cut is being fed on the table it passes under a punch-head 29, which is operated through a connecting-rod 30 from a crank 31 on the main shaft. This makes the cuts requisite for forming the rounded and narrow end, the tongue, and the eye before the band is cut from the strip. The cuts for the rounded ends are made by a punch 32, carried by the head, which notches one side of the strip, the sides of each notch forming one side of the rounded end of one strip and the other side of the rounded end of the adjoining strip. This punch passes through a

stripper and die 33. The tongue is cut and raised by the die 34, carried by the head, in connection with the punch 35, which underlies the strip. (See Fig. 35.) These operate through a pair of stripper-plates 36 36. The punch is operated from underneath through a punch-rod 37. The punch-rod is supported at its lower end by a lever 38, fulcrumed at the middle. The head which carries the die also carries a push-rod 39, which is screwed into the head. The amount of lift of the punch and the cut for the tongue is adjusted by adjusting the length of the push-rod and adjusting the stop-screw 40. The eye is cut by a punch 41, operated by the head, which passes through a stripper and die 42, formed in the same block with the die for cutting the rounded ends of the band. The head 85 also carries a lettered punch 43 for impressing on the band the name of the article and the patent-mark and a shear-blade 44, which coöperates with a blade 45, which underlies the strip. The punches, die, and blade carried by the head are all made fast to a punch-block 46, bolted to the head. The dies and stripper-plates are fastened to a die-block 47. A dowel 48, attached to the punch-block, and a leading pin on the punch 32 for the rounded ends enter dowel-holes 49 and 50 in the die-block and facilitate the positioning of the blocks. Guide-fingers 51 and 52, fixed at the end of the table, and a leading-finger 53, carried by the head behind the shear-blade, deflect the forward edge of the strip downward as it is fed under the shear-blade, and the leading-finger is pushed back slightly against a spring 53^a. The leading-finger is held slightly nearer to the shearing edge than the width of the band and is pushed back when the strip is fed against it. As soon as the band is sheared the leading-finger springs forward and throws the band flat against the end of the die-block. The band then falls edgewise into the V-groove 110 formed with the end of the die-block by the finger 51 and a finger 54, carried by the band-pusher 55. The band-pusher is operated from the reciprocating element 19, which operates the strip-feeding mechanism. A cam-roll 56, attached to this reciprocating element, engages the arms of a segment 57 and oscillates the segment. The segment meshes with a rack 58 on the band-pusher. This movement takes place when the reciprocating element is about midway of its movement. The band-pusher pushes the band endwise into a coiling-head 59, through a slot 60 in the head. As it enters, the end, with the tongue, passes between the coiling-spindle 61 125 and a coiling-blade 62, attached to the side of the spindle and separated therefrom at the lower end. The end of the band, with the tongue, is pushed past a rib 63 in the coiling-head and across the recess 63^a. At this time 130 the coiling-blade is opposite the recess 64 and can open away from the spindle sufficiently to allow the band and projecting tongue to pass between. The coiling-head is open on

the front side, and this side is partly closed by a plate 65, which is held in place by two pins 66 67 and a spring 68. The coiling-head is supported from the frame of the machine by a stud 69. A latch 70 holds it to the stud. By lifting this latch it can be quickly detached from the stud and pulled off from the spindle in case a defective band should become caught on the spindle and require removal by hand. The spindle is supported near its upper end in a bearing 71, attached to the framework of the machine, and it is guided lower down by a bearing 72, which is carried by the head for the band - cutting punches and dies. The spindle is revolved intermittently in a clockwise direction two revolutions at a time at each stroke of the machine. The connections for revolving the spindle are the arm 73, attached to the rock-shaft 16, connecting-rod 74, rack 75, pinion 76, ratchet 77, and pawl 78 in a head 79, which is made fast to the upper end of the spindle. A brake 80 serves to check the momentum of the spindle when the rack has completed its driving stroke, and thereby insures the stoppage of the spindle always at the same point in its revolution. It also overcomes any possible sticking of the pawl and ratchet on the back stroke and prevents the spindle from turning or becoming displaced backwardly. The spindle at the place where the band is coiled is of less diameter than the finished band, so that the ends of the band when coiled will overlap sufficiently to allow the end of the tongue to enter the eye. The spindle is flared or tapered below the point where the band is coiled and is the full size of the finished band at its lower end. Three longitudinal grooves are cut in the spindle to receive the ejector-blades 81. These blades are attached to a collar 82, which is carried up and down with the head for the band - cutting punches and dies. When the end of the band is inserted, the flared ends of the ejector-blades are below the band. These rise before the spindle commences to revolve, and the ejector-blade opposite the recess 63^a bends the end of the band, as shown in Fig. 42, into the recess, thereby throwing out the tongue sufficiently to insure its engagement by the coiling-blade. When the band is coiled, the lower ends of the ejector-blades are above the point where the coiling takes place. The coiled band is pushed downwardly by these blades over the flared portion of the spindle, thereby expanding the band and securely hooking the ends, and off from the lower end of the spindle. A dial-feed for assembling the parts of the cap, consisting of a carrier-ring 83 with holes 84 of the exact outside size of the finished cap, is revolved intermittently under the spindle in an anti-clockwise direction by a pawl 85, carried by the reciprocating element 19, which engages the notches 86 in hardened-steel blocks set in the edge of the carrier-ring. One of the holes is brought into register under the spindle and receives the coiled

band as it is pushed off from the spindle. The bands are next carried by the carrier-ring to the other side of the machine, where 70 the top plates are formed and inserted.

Strip-feed for top plates.—The strips from which the top plates are cut are conveniently of the same length as the strips for the holding-bands, but narrower. They are about 75 one and one-half inches in width, and each strip furnishes thirteen blanks for the top plates. These strips are therefore used up more than twice as fast as the strips for the bands and so rapidly that the attendant cannot conveniently feed them singly to the machine as the other strips are fed. The feeding mechanism for these strips is therefore devised to receive a number at a time. The strips are piled on a support 87. Magnets 85 88 are provided for picking up the strips one at a time from this support, and laterally - feeding fingers 89 transfer the lifted strips at each thirteenth stroke of the machine to the right, and the right-hand edge 90 at the forward end will lie between a slide 90 and a longitudinally-feeding dog 91, pivoted to the slide, and be fed between the punch and die for cutting and forming the top plates and inserting them in the holding-bands in the holes of the dial-plate. All of 95 these feeding devices are operated from the rock-shaft 16 through the arm 92 and rod 93. A pawl 94 engages a thirteen-toothed ratchet 95 on the shaft 96 and spaces or moves it one tooth at each stroke of the machine. Two cams formed in one piece are carried by the shaft 96. One of the cams 97 engages a roller 98, attached to the vertical rod 99, with the cross - bar 100, and effects the lifting and 105 lowering of the magnets. The laterally-movable fingers are attached to a shaft 101, which is rocked by the cam 102 through the cam-roll 103 on the end of the arm 104. The magnets and these fingers lift a strip from the 110 pile on the support and shift it laterally between the slide and the longitudinally-feeding dog at each revolution of the cam and every thirteenth stroke of the machine. The longitudinally-feeding dog is actuated also 115 from the rod 93, acting through the lever 105, rock-shaft 106, lever 107, and rod 108. This operates on the forward stroke to first force the dog against the strip to be fed, thereby clamping it against the slide, and then carry 120 the slide forward with the strip. On the return stroke the dog is first lifted and then carried rearwardly with the slide. A friction-clamp 109 bears against the slide and prevents its movement until after the dog has 125 moved. Stop-screws 110 and 111 are a means for adjusting and limiting the movement of the slide. When the last plate has been cut from the strip, the scrap is kicked out by the lever 112 with a hooked end 112^a, which 130 catches in one of the holes in the scrap. This hooked end is pivoted to the lever 112. A spring 112^b serves the double purpose of drawing the hook into engaging position and op-

erating the lever and hook to kick out the scrap. This is operated by a pin 113 in the side of the ratchet-wheel striking one arm of the lever 114, the other arm of which strikes 5 the lever with the hook. This brings the lever into engagement with the scrap. The lever 114 is pivoted at 114^b.

Top-plate punching and drawing mechanism.—The strips from which the top plates ^p 10 are punched are fed between a combination punch and drawing-plunger and die. The punch 115 is screwed to the punch-head 116 and the punch-head is operated from the main shaft of the machine by two lifting-cams 117 15 117 and two punch-driving cams 118 118, which are shaped so as to give a dwell to the punch at the bottom of its stroke. Yokes 119 119 surround the cams and carry cam-rolls 120 120, which are engaged by the lifting-cams, and 20 rolls 121 121, which are engaged by the punch-driving cams. Screw connections are made between the yokes and head for the purpose of accurately adjusting the movement of the punch. These connections consist of screws 25 122 122, projecting downwardly from the yokes into nuts 123 123, which have collars formed on them to engage the punch-head. Worm-teeth are cut in the periphery of the nuts, and the teeth are engaged by two worms 30 124 124 on the same shaft for the purpose of simultaneous adjustment of the nuts. A spring-pressed clamping-collar 125 surrounds the punch and clamps the strip of sheet metal from which the blanks for the top 35 plates are punched against the rim of the die 126 while the blanks are being punched. The cams for operating the punch are so formed that when the punch reaches the bottom of its stroke it will dwell for a period of time 40 40 while the edges of the blank are confined between the end of the punch and the bottom of the die and the top plate is drawn to flange the edge. There is a hole through the punch, and a plunger 127 passes through the punch 45 45 and forces the blank through a hole in the die. The plunger is operated from a crank 128 on the main shaft through the pitman 129. In advance of the operation of the plunger an expanding-pin 130, with a slightly 50 rounded or tapered end, is forced up from underneath the table of the machine into the band within the hole in the carrier-ring which is under the die. Its purpose is to open out and size the band and press down 55 the tongue. The overlying die prevents the band from being pushed out of the carrier-ring by the expanding-pin. This pin is positively operated in both directions from two cams 131 132, formed on the crank-disk 13, 60 acting on the rocker-arms 133 134, and through the rod 135, arm 136, rock-shaft 137, and arm 138, to which the expanding-pin is attached. As the expanding-pin is retracted the plunger after drawing the flange on the top plate 65 65 forces it through the die and into the band in the underlying hole of the carrier-ring.

Four strippers 139 lie in radially-disposed grooves in the under side of the die-block and are pushed by springs 140 into the path of the plate and plunger. They are beveled at 70 their ends, so that the top plates and plunger will push them out of the way in descending. They engage the edges of the band and top plate and hold them in the carrier-ring when the plunger is withdrawn. The top 75 plate having been formed and inserted in the coiled and locked band, the parts are carried next by the carrier-ring to the edge-turning mechanism. While being carried by the carrier-ring to this mechanism the band is kept 80 from falling through the hole in the ring by a guard-rail 141, underlying the carrier-ring. The top plate remains in place by reason of its snug fit in the band. If there should be no band in a hole in the carrier-ring into 85 which a top plate is fed, the top plate will fall through the ring and out of the machine, as there is sufficient open space between the bottom of the carrier-ring and the guard-rail. A top plate without a band is consequently 90 never carried to the edge-turning mechanism.

Edge-turning mechanism.—The edge-turning mechanism consists of an edge-turning die 142, fixed in the framework of the machine under the carrier-ring, and a plunger 143, 95 which is carried by the head 29, to which the punches for the bands are attached. This die and plunger turn inwardly one of the curved edges of the band to hold the top plate. A stripper-finger 144, which lies in a groove 100 in the plunger, prevents the pulling out of the bands on the retraction of the plunger in the event of no top plate being in the band. The plunger for this mechanism is provided with a leading-pin 145, which normally projects below the end of the plunger and is 105 kept in this relation by the spring 146. When the plunger descends, the top plate is first pushed down against the edge-turning die and clamped against the die by the leading-pin. Further downward movement of the plunger compresses the spring, and a shoulder on the plunger engages the uppermost edge 110 of the band and forces the band downward and drives the lowermost edge between the 115 die and top plate, thereby turning inwardly this edge. This is the final operation in the formation of the metal portion of the cap. When the plunger returns, the leading-pin 120 strips off the cap.

Cork-feeding mechanism.—The cork disks ^c for the caps are loaded in a tubular magazine 147, which is removable from the machine. It is slotted on one side for convenience of access in case the disks should become wedged or misplaced in the magazine. At the lower end is a gate 148, which is closed when the magazine is taken from the machine and is being loaded. The cork disks are delivered from the magazine through a tube 149 125 130 in front of a transfer-slide 150 at a point inside the line of holes in the carrier-ring. The

depth of the slide is less than the thickness of a cork disk. At each stroke it pushes out the lowest cork disk in the tube and transfers it to a point on the line of holes in the carrier-ring and one space beyond the edge-turning mechanism. The slide operates in synchronism with the punch which cuts out the top plates, as this is a convenient time for its operation, and its movement can be effected 5 by connection with the mechanism for operating the punch in a simple manner. The connection is from one of the yokes for operating the punch-head through the rod 151, bell-crank lever 152, and latch 153, pivoted 10 to the slide and engaging one end of the lever. When this latch is not in engagement, the slide remains in the forward position. The engagement of the latch with the lever depends on the presence of a top plate in the 15 hole of the carrier-ring at the edge-turning mechanism at the time when the lever commences to move, for if a top plate is interposed between the plunger and the edge-turning die a detector-pin 154 is pushed down. 20 This detector-pin is operatively connected, through the rod 155, with a lever 156, which throws the latch into engagement with the bell-crank lever. The lever commences to move back at about the same moment that 25 the plunger does. If, on the other hand, there is no cap in the hole in its carrier-ring at the edge-turning mechanism, then the bell-crank lever commences its reciprocation without the slide, and when the empty hole is 30 spaced to its position under the slide no cork disk will be fed into it. The counting mechanism 157 is operatively connected to this slide through the lever 158 and rod 159. It therefore counts only the caps actually made 35 40 by the machine instead of the revolutions of the machine.

Cork-inserting and cap-ejecting mechanism.—Over the point where the cork disks are fed into the caps in the carrier-ring is a 45 plunger 160, carried by the head, to which the punches for the bands are attached. A leading-pin 161 is set in the end of the plunger. A spring 162 behind this pin pushes the pin outwardly, and it throws off the cap 50 on the return of the plunger. A stop-pin 163, operated through the lever 164 from the rock-shaft 137, meets the plunger when it first descends and supports the cap while the cork disk is pushed in. The plunger and stop-pin 55 then descend together, and the cap is pushed out through the bottom of the carrier-ring. An ejector 165, operated by the reciprocating element 19, pushes the finished caps off from the stop-pin, and they then drop out from the 60 machine.

Safety devices.—The machine is driven, as is usual in sheet-metal presses, by a belt on a fly-wheel 166. The fly-wheel is loose on the driving-shaft. Adjoining the pulley on the 65 shaft is a driving-collar 167, fast to the shaft. A bolt 168, carried by the collar, engages a

notch on the fly-wheel and effects the coupling. A hook 169 is formed on one end of the bolt, by which it is retracted when it encounters the end of the latch 170. This it 70 does in the position of the driving-shaft in which the punch-heads are uppermost. This is consequently the position of the machine in which the machine always stops, and the parts are shown in this position in the drawings which show the assembled machine. To start the machine, the latch is pulled out of the way of the hook on the end of the bolt by depressing a treadle 171. The treadle and latch are connected by the rod 172. On release of the treadle it is drawn up by a spring 173, and the bolt is retracted and the machine stopped as soon as the shaft reaches the position in which the punch-heads are at the uppermost position of their movement. A 80 second latch 174, automatically operated, is also placed in the path of the hook on the bolt. This lever is thrown into the path of the hook at each revolution of the machine by a cam 175 acting on the bell-crank lever 90 176, which is connected to the latch by a link 177. The cam allows the lever to be retracted by a spring 178 just before the bolt reaches it. In operative connection with the latch through a rock-shaft 179 and arm 180 is a 95 bolt-rod 181. The lower end of this rod enters a spacing-notch of the carrier-ring when the latch is retracted; but in the event of the carrier-ring failing to space properly the bolt-rod cannot descend and the latch will not be 100 retracted. The latch will then withdraw the bolt 168 and stop the machine before the punches have descended far enough to do any injury.

The weight of the punch-heads and attached parts is counterbalanced by a spring 182, which is connected to the crank-disk 13 by the rod 183.

What we claim as new, and desire to secure by Letters Patent of the United States, is— 110

1. In a strip-feed mechanism, the combination of two notched feeding-bars, feeding-dogs carried by the feeding-bars, forward-feeding pawls, rearward-feeding pawls, means for operating the pawls for feeding one bar 115 forward and the other rearward, and means for exchanging the engagement of the pawls and feeding-bars.

2. In a strip-feed mechanism, the combination of two notched feeding-bars, feeding-dogs carried by the feeding-bars, a longitudinally-movable slide, forward-feeding pawls and rearward-feeding pawls carried by the slide, means for operating the longitudinally-movable slide for feeding one bar forward 125 and the other rearward, and means for exchanging the engagement of the pawls and feeding-bars.

3. In a strip-feed mechanism, the combination of notched feeding-bars, feeding-dogs 130 carried by the feeding-bars, a transversely-movable slide, forward-feeding pawls and

rearward-feeding pawls carried by the slide, means for operating the pawls for feeding, and means for operating the transversely-movable slide to exchange the engagement of the pawls and feeding-bars.

4. In a strip-feed mechanism, the combination of notched feeding-bars, feeding-dogs carried by the feeding-bars, a longitudinally-movable slide, a transversely-movable slide carried by the longitudinally-movable slide, forward-feeding pawls and rearward-feeding pawls carried by the transversely-movable slide, means for operating the longitudinally-movable slide for feeding, and means for operating the transversely-movable slide to exchange the engagement of the pawls and feeding-bars.

5. In a strip-feed mechanism, the combination of two notched feeding-bars, feeding-dogs carried by the feeding-bars, a transversely-movable slide, a pawl for feeding the bars in one direction and two pawls for feeding the bars in the contrary direction carried by the slide, means for operating the pawls for feeding, and means for operating the slide to exchange the engagement of the pawls and feeding-bars.

6. In a strip-feed mechanism, the combination of notched feeding-bars, feeding-dogs carried by the feeding-bars, forward-feeding pawls, rearward-feeding pawls, means for reducing the effective stroke of the forward-feeding pawls, means for operating the pawls for feeding, and means for exchanging the engagement of the pawls and feeding-bars.

7. In a strip-feed mechanism, the combination of two notched feeding-bars, feeding-dogs carried by the feeding-bars, a transversely-movable slide, a forward-feeding pawl and two rearward-feeding pawls carried by the slide, means for reducing the effective stroke of the forward-feeding pawl, means for operating the pawls for feeding, and means for exchanging the engagement of the pawls and feeding-bars.

8. In a strip-feed mechanism, the combination of notched feeding-bars, feeding-dogs carried by the feeding-bars, forward-feeding pawls, rearward-feeding pawls, a ratchet-wheel, means for operating the pawls for feeding and for spacing the ratchet-wheel, and means operated at definite positions of the ratchet-wheel for exchanging the engagement of the pawls and feeding-bars.

9. In a strip-feed mechanism, the combination of notched feeding-bars, feeding-dogs carried by the feeding-bars, a longitudinally-movable slide, a transversely-movable slide carried by the longitudinally-movable slide, forward-feeding pawls and rearward-feeding pawls carried by the transversely-movable slide, a ratchet-wheel, a pawl for the ratchet-wheel, means for operating the pawl for the ratchet-wheel and the longitudinally-movable slide for feeding, and means operated at definite positions of the ratchet-wheel for op-

erating the transversely-movable slide to exchange the engagement of the pawls and feeding-bars.

10. In a band-cutting mechanism, the combination of shear-blades, means for operating the blades, and a strip-feed consisting of notched feeding-bars, feeding-dogs carried by the feeding-bars, sets of feeding-pawls for both directions, and means for simultaneously operating both sets of pawls for feeding the bars in contrary directions, and means for alternating the direction of feed of the bars.

11. In a band-cutting mechanism, the combination of an eye-cutting punch and die, a tongue-cutting punch and die, shear-blades, means for operating these parts, and a strip-feed consisting of notched feeding-bars, feeding-dogs carried by the feeding-bars, sets of feeding-pawls for both directions, and means for simultaneously operating both sets of pawls for feeding the bars in contrary directions, and means for alternating the direction of feed of the bars.

12. In a band cutting and feeding mechanism, the combination of a strip-feed mechanism, means for operating the strip-feed mechanism, shear-blades, means for operating the blades, a band-pusher, and means for operating the band-pusher.

13. In a band cutting and feeding mechanism, the combination of a horizontal strip-feed mechanism, means for operating the strip-feed mechanism, shear-blades, fingers for turning edgewise the bands sheared from the strips, a band-pusher, and means for operating the band-pusher.

14. In a band-coiling mechanism, the combination of a spindle, a blade attached to the side of the spindle and separated therefrom at one end, a band-pusher, means for operating the band-pusher toward the end of the band between the blade and spindle and means for revolving the spindle intermittently.

15. In a band-coiling mechanism, the combination of a spindle, a blade attached to the side of the spindle and separated therefrom at one end, a coiling-head, a rib in the coiling-head for bending the end of the band and throwing out the tongue formed thereon, and means for revolving the spindle intermittently.

16. In a band-coiling mechanism, the combination of a spindle, a blade attached to the side of the spindle and separated therefrom at one end, a coiling-head, a rib in the coiling-head for bending the end of the band and throwing out the tongue formed thereon, a band-pusher, means for operating the band-pusher to insert the end of the band between the blade and spindle and bend it against the rib in the coiling-head, and means for revolving the spindle intermittently.

17. In a band-coiling mechanism, the combination of a spindle with a flaring end, a blade attached to the side of the spindle and

separated therefrom at the end toward the flaring end of the spindle, a coiling-head, ejector-blades, means for revolving the spindle intermittently, and means for operating the ejector-blades.

18. In a band-coiling mechanism, the combination of a spindle, a coiling-head partly surrounding the spindle and open at one side, and a plate for partially closing the open side of the head.

19. In a band-coiling mechanism, the combination of a spindle, a coiling-head partly surrounding the spindle and open at one side, a plate for partially closing the open side of the head, and a latch connection between the coiling-head and the framework.

20. In a mechanism for assembling bottle-caps, the combination of a carrier-ring, means for spacing the carrier-ring, means for inserting bands in the carrier-ring, and means for inserting top plates in the bands.

21. In a mechanism for assembling bottle-caps, the combination of a carrier-ring, means for spacing the carrier-ring, means for inserting bands in the carrier-ring, and a plunger for drawing top plates and transferring the drawn top plates to the bands in the carrier-ring.

22. In a mechanism for assembling bottle-caps, the combination of a carrier-ring, means for spacing the carrier-ring, means for inserting bands in the carrier-ring, means for inserting top plates in the bands, and an edge-turning mechanism for turning an edge of each of the bands.

23. In a mechanism for assembling bottle-caps, the combination of a carrier-ring, means for spacing the carrier-ring, means for inserting bands in the carrier-ring, a plunger for drawing top plates and transferring the drawn top plates to the bands in the carrier-ring, and an edge-turning mechanism for turning an edge of each of the bands.

24. In a mechanism for assembling bottle-caps, the combination of a carrier-ring, means for spacing the carrier-ring, means for inserting bands for the caps in the carrier-ring, means for inserting top plates in the bands, and means for inserting cork disks in the assembled bands and top plates.

25. In a mechanism for assembling bottle-caps, the combination of a carrier-ring, means for spacing the carrier-ring, means for inserting bands for the caps in the carrier-ring, a plunger for drawing top plates and transferring the drawn top plates to the bands in the carrier-ring, and means for inserting cork disks in the assembled bands and top plates.

26. In a mechanism for assembling bottle-caps, the combination of a carrier-ring, means for spacing the carrier-ring, means for inserting bands for the caps in the carrier-ring, means for inserting top plates in the bands, an edge-turning mechanism for turning an edge of each of the bands, and means for in-

serting cork disks in the assembled bands and top plates.

27. In a mechanism for assembling bottle-caps, the combination of a carrier-ring, means for spacing the carrier-ring, means for inserting bands for the caps in the carrier-ring, a plunger for drawing top plates and transferring the drawn top plates to the bands in the carrier-ring, and an edge-turning mechanism for turning an edge of each of the coiled bands.

28. In a bottle-cap-making machine, the combination of a band-coiling mechanism, a dial-feed mechanism, means for transferring the coiled bands to the dial-feed mechanism, a top-plate-punching mechanism, and means for transferring the punched top plates to the coiled bands in the dial-feed mechanism.

29. In a bottle-cap-making machine, the combination of a band-cutting mechanism, a band-coiling mechanism, means for transferring the bands to the band-coiling mechanism, a dial-feed mechanism, means for transferring the coiled bands to the dial-feed mechanism, a top-plate-punching mechanism, and means for transferring the punched top plates to the coiled bands in the dial-feed mechanism.

30. In a bottle-cap-making machine, the combination of a band-coiling mechanism, a dial-feed mechanism, means for transferring the coiled bands to the dial-feed mechanism, a top-plate-punching mechanism, and a plunger for drawing the top plates and transferring the drawn top plates to the coiled bands in the dial-feed mechanism.

31. In a bottle-cap-making machine, the combination of a band-cutting mechanism, a band-coiling mechanism, means for transferring the bands to the band-coiling mechanism, a dial-feed mechanism, means for transferring the coiled bands to the dial-feed mechanism, a top-plate-punching mechanism, and a plunger for drawing the top plates and transferring the drawn top plates to the coiled bands in the dial-feed mechanism.

32. In a bottle-cap-making machine, the combination of a carrier-ring for bands, means for spacing the carrier-ring, an expanding plunger for expanding the bands in the carrier-ring, a top-plate-punching mechanism, and a plunger for drawing the top plates and transferring the drawn top plates to the bands in the carrier-ring.

33. In a bottle-cap-making machine, the combination of a band-coiling mechanism, a carrier-ring, means for transferring the coiled bands to the carrier-ring, means for spacing the carrier-ring, an expanding-plunger for expanding the bands in the carrier-ring, a top-plate-punching mechanism and a plunger for drawing the top plates and transferring the drawn top plates to the bands in the carrier-ring.

34. In a bottle-cap-making machine, the

combination of a band-coiling mechanism, a carrier-ring, means for transferring the coiled bands to the carrier-ring, means for spacing the carrier-ring and an edge-turning mechanism for turning one of the curved edges of each of the coiled bands.

35. In a bottle-cap-making machine, the combination of a band-coiling mechanism, a carrier-ring, means for transferring the coiled bands to the carrier-ring, means for spacing the carrier-ring, a top-plate-punching mechanism, and a plunger for drawing the top plates and transferring the top plates to the bands in the carrier-ring, and an edge-turning mechanism for turning an edge of each of the coiled bands.

36. In a bottle-cap-making machine, the combination of a band-coiling mechanism, a carrier-ring, means for transferring the coiled bands to the carrier-ring, an expanding-plunger for expanding the bands in the carrier-ring, a top-plate-punching mechanism, a plunger for drawing the top plates and transferring the top plates to the bands in the carrier-ring, and an edge-turning mechanism for turning an edge of each of the coiled bands.

37. In a mechanism for inserting cork disks in bottle-caps, the combination of a carrier-ring for bottle-caps, means for spacing the carrier-ring, a feeding mechanism for the cork disks, means for operating the feeding mechanism, a latch connection between the feeding mechanism and its operating means, a latch-closing means, a detector-pin for operating the latch-closing means, and means for forcing the caps against the detector-pin.

38. In a mechanism for inserting cork disks in bottle-caps, the combination of an edge-turning mechanism, a carrier-ring for bottle-caps, means for spacing the carrier-ring, a feeding mechanism for the cork disks, means for operating the feeding mechanism, a latch connection between the feeding mechanism and its operating means, a detector-pin for operating the latch-closing means, and an

edge-turning mechanism which also acts as a means for forcing the caps against the detector-pin.

39. In a mechanism for assembling bottle-caps, the combination of a carrier-ring, means for spacing the carrier-ring, means for inserting bands for the caps in the carrier-ring and supporting them therein, means for inserting top plates in the bands, a counting mechanism, means for spacing the counting mechanism synchronously with the operation of the other mechanism, a latch connection between the counting mechanism and its spacing means, a detector-pin for operating the latch-closing means, and means for forcing the top plates of the caps against the detector-pin.

40. In a bottle-cap-making machine, the combination of a band-coiling mechanism, a carrier-ring, means for transferring the coiled bands to the carrier-ring, an expanding-plunger for expanding the bands in the carrier-ring, a top-plate-punching mechanism, and a plunger for drawing the top plates and transferring the drawn top plates to the bands in the carrier-ring.

41. In a bottle-cap-making machine, the combination of a band-coiling mechanism, an edge-turning mechanism, a carrier-ring, means for transferring the coiled bands to the carrier-ring, means for spacing the carrier-ring, an expanding-plunger for expanding the bands in the carrier-ring, a top-plate-punching mechanism, and a plunger for drawing the top plates and transferring the drawn top plates to the bands in the carrier-ring.

Signed in the borough of Brooklyn, city of New York, N. Y., this 6th day of May, 1902.
